 215/223, 341, 213, 205—221, 224, 225

FIG. 3 is a sectional view taken on the line 3—3 of FIG.
 1.

[56] References Cited

The characteristic features of my new design reside in a
 sealing liner for a closure having a peripheral vertical
 wall which is beveled at its upper outer edge, in
 combination with a central boss which has a vertical
 wall and has a width of approximately one-third the
 diameter of the sealing liner, for a closure and a height
 approximately twice the height of the peripheral wall.
